INTERNAL COMBUSTION ENGINE

Lionel M. Woolson, deceased, late of Detroit, Mich., by Emma F. Woolson, executrix, Bloomfield Village, Mich., assignor to Packard Motor Car Company, Detroit, Mich., a corporation of Michigan

Application July 21, 1930. Serial No. 469,327

11 Claims. (Cl. 123—179)

This invention relates to internal combustion engines and more particularly to engines of the compression-ignition type in which fuel is injected into the combustion chamber through 5 mechanism actuated by an engine part.

The invention has to do more particularly with the starting of engines in which liquid fuel is injected into the compressed air charges at a pressure developed in accordance with the engine 10 speed. With this type of engine, the degree of fuel atomization and the pressure at which the fuel is injected becomes less as the speed of the engine is reduced and, therefore, the fuel is not injected into the compressed air in the combustion 15 chambers under a pressure or in an atomized condition conducive to the formation of a mixture which will result in quick starting when the crank shaft is being turned slowly by a source of internal power.

20 An object of the invention is to regulate the timing, the pressure and the atomization of liquid fuel charges injected into compressed air charges in the cylinders of a compression-ignition engine in a manner to promote the formation of a mixture which will readily ignite under compression while the engine is being turned over in the starting.

Another object of the invention is to provide an internal combustion engine of the compression- 30 ignition type in which the timing of the fuel injection and the pressure produced upon the injected fuel charges is automatically increased beyond the pressure developed by the mechanism, operating the fuel injection devices when the 35 engine is running under its own power, during cranking of the engine.

A further object of the invention is to provide an automatic control for regulating the actuation of the fuel injection devices of a compression- 40 ignition engine so that, during cranking, the fuel charges will be injected into the combustion spaces when the compressed air charges are substantially at their highest compression and under a pressure such that there is sufficient 45 penetration of the air charges by the fuel charges to result in a homogeneous mixture which is thoroughly intermingled in a short space of time.

Still another object of the invention is to provide 50 an automatic control which is actuated during the application of a starter to an engine of the compression-ignition type to bring into effective relation a faster moving fuel pump actuating cam mechanism and at a later time in the compression stroke of the engine pistons than the

time at which the injection takes place when the engine is operating under its own power.

These and other objects of the invention will appear from the following description taken in connection with the drawings, which form a part 60 of this specification and in which:

Fig. 1 is a rear elevational view of a radial engine partially broken away and partially in section to show a fuel injection device and the actuating mechanism therefor, the cams being in 65 a relation with the slower cam in effective position;

Fig. 2 is an elevational view showing the fuel injection mechanism, actuating cams arranged with the faster cam in effective position; 70

Fig. 3 is a sectional view taken on the line 3—3 of Fig. 1;

Fig. 4 is a sectional view taken on the line 4—4 of Fig. 3;

Fig. 5 is a sectional view of one of the nozzle 75 portions of a fuel injection device.

Referring now to the drawings by characters of reference, 10 represents generally the crank case of a compression-ignition type of internal combustion engine from which nine air-cooled 80 cylinders 11 extend radially, the cylinders being secured under compression around the wall of the crank case by compression rings, one of which is indicated at 12. The cylinders are formed with an integral dome 13 and secured upon each 85 of the domes is a head 14. Each of the associated heads and domes are formed with a single Venturi passage 15 leading into the interior of the associated cylinder, such passages serving as both the air inlet and the exhaust outlet for the combustion chambers which are between the cylinder domes and the pistons 16. In order to control the passages 15, there is provided with each a valve 17 which is normally closed by a plurality of springs 18 and opened by conventional engine actuated mechanism including a push rod 19 which extends into the crank case. 90

A diaphragm, or internal wall 20 is secured within the crank case and is formed with a central opening in which is arranged a bearing 21 100 for supporting the rear end of the crank shaft 22, the crank shaft projecting axially through the crank case. Arranged in a relation substantially parallel to the diaphragm is a detachable rear wall 23 which closes the open end of 105 the crank case, and detachably secured to the rear wall is a starting device, indicated generally at 24, which is preferably of the inertia type as illustrated in Patent No. 1,739,469, issued December 10, 1929, to R. P. Lansing. Such start- 110

ing device is arranged with a manually operable axially reciprocable jaw 25 which projects into the crank case in alignment with the rear end of the crank shaft, so that it can be moved into a 5 cranking relation.

The engine illustrated is of the compression-ignition, or Diesel type, which operates on a four-stroke cycle, air charges being drawn into the cylinders through the passages 15 upon the 10 suction strokes of the pistons, during which time the valves 17 are mechanically held open. The valves are next closed and the compression strokes then occur, and during the compression strokes, charges of fuel oil are injected under a high pressure at any engine speed and in an atomized 15 condition into the air charges being compressed, such that the mixture thereof with the compressed air will form a charge of a character producing quick combustion. There is associated with each cylinder a fuel injection device 20 which consists generally of a nozzle portion 26 and a pump portion 27, the nozzle portions being secured rigidly to the cylinders and arranged to project through the walls thereof so that the 25 fuel charges can be injected directly into the interior of the cylinders.

Each nozzle consists of a barrel 28 having a detachable end 29 extending through the associated cylinder wall and formed with a conical 30 outlet opening in which the valve head 30 is arranged. The valve stem 31 is arranged to be moved into engagement with the stop member 32 by a spring 33 and such stop member is adjusted to prevent the valve from entirely closing. 35 The barrel 28 is formed with a downwardly extending neck portion which is provided with a passage 34 leading to the hollow chamber in the barrel through which the valve rod extends. Such nozzle neck is screwed into the casing 35 of the associated pump unit and bears against a spacer 36 which maintains the pump barrel 37 in position within the casing 35, there being a pair of spring-pressed valves 38 associated with the spacer and the barrel to prevent liquid fuel 40 returning to the pump structure from the nozzle structure. A plunger 39 is arranged to reciprocate within the pump barrel and a fuel inlet manifold 40 communicates with all of the pumps, there being a union 41 in the manifold structure 45 associated with each of the barrels, and ports 42 extend through the casing and the barrel to establish communication between the fuel feeding manifold and the interior of the barrel. Such ports are controlled by the position of the plunger 50 so that when a plunger uncovers the ports 42, liquid fuel is moved into the pump barrel and nozzle, under a low pressure from the source of supply (not shown), completely filling the chambered portions therein. The pump plungers are 55 moved in their injection strokes by adjustable mechanism, which will be hereinafter described, and during such movement they close the ports 42, their stroke after closing such ports determining the quantity of fuel which is displaced 60 from the nozzle into the cylinders.

It will be seen that the speed of the plunger movement determines the degree of pressure under which the fuel charge is forced past the nozzle valve head. The effective stroke of the 70 plungers will force fuel past the valves 31 and from the nozzles in a manner such that the fuel charges are directed into the cylinders in a conical spray. The air inlet passages are formed and arranged so that they cause rotation of the air in 75 the cylinders and such rotation continues during

the following compression stroke of the piston, the fuel charges being sprayed into such compressed rotating air charges.

The degree of fuel atomization and the extent of the pressure at which it is injected determines the degree of the intermingling of the oil with the air and, therefore, it is necessary that there be sufficient atomized fuel penetration of the air to cause a uniform distribution if efficient engine operation is to result. It is also necessary that the atomization and penetration of the air by the fuel oil be of a certain character if combustion is to be attained when the cylinders are cold, as they are when starting. With the type of injection mechanism described, in which the pressure behind the fuel varies in accordance with the crank shaft speed, difficulty is experienced when turning the crank shaft at a slow speed in starting the engine to produce a sufficient pressure behind the fuel charges, because of the consequent slow movement of the fuel pumps, to cause sufficient atomization and penetration of the compressed air charges to produce a mixture which will support combustion.

This invention has to do particularly with a mechanism for injecting fuel oil in an atomized condition and at a sufficient pressure to cause an intermingling with the compressed air in the cylinders such that ignition will readily result from compression when the crank shaft is being slowly turned through the application of a starting device. To this end, I utilize the regular fuel injecting mechanism for the normal running operation of the engine and provide an auxiliary actuating mechanism therefor which is effective only during the application of the starting mechanism to the crank shaft. This auxiliary actuating mechanism is made effective automatically through application of the starting device and is placed in ineffective relation when the starting device is released. In carrying out such invention, I propose that the liquid fuel charges will be injected, during the turning of the crank shaft by the starting device, at a pressure which will cause the fuel to penetrate substantially to the center of the cylinder and in a finely atomized condition so that one rotation of the compressed air in the cylinder will cause a uniform distribution therein of the atomized liquid fuel.

Under normal running operation, crank shaft actuated mechanism is provided for causing the pump plungers to move in their injection strokes, and such mechanism is returned to a position uncovering the ports 42 by means of the coil spring 43. A fuel plunger push rod 44 extends through the crank case and has associated therewith a rod 45 which is pivotally connected with a link 46 carried by a regulating ring 47 rotatably mounted within the crank case. The ring 47 can be actuated through the association of a tooth segment 48 with a rack 49 which is fixed to the ring, the segment being rotated by means of the shaft 50 which is in turn actuated through suitable mechanism connected with the lever 51. Associated with each of the levers 45 is a slipper or rock lever, as shown at 52, 53 and 54, each being carried by a shaft 55 supported by the diaphragm and the rear casing cover 23. The free ends of the slippers are formed with a curved groove in which the associated rod 45 is adjustably positioned by rotation of the ring 47 and the connecting links 46, so that upon movement of the rods 45, lengthwise of the slippers, the effective stroke of the pump plungers can be simultaneously varied.

Arranged interiorly of the pivoted slippers 53, for actuating the same to cause an injection stroke of the pump plungers, is a cam 56 which is provided with four lobes 57, 58, 59 and 60. A cam 56 is also provided with a plurality of lobes 61 arranged in a parallel plane with the lobes 57, 58, 59 and 60 and at the rear thereof for actuating the slippers 62, one of which is pivotally mounted upon each of the shafts, and one of the rods 19 is associated with each of the slippers 62. Upon rotation of the cam 56 the lobes 61 will cause movement of the valve operating mechanisms to open the ports 15 in desired timed relation with the engine cycle.

A cam 63 is mounted upon the rear end of the crank shaft and is provided with an extended hub 64 which is keyed to the crank shaft as indicated at 65, a suitable bearing ring 66 being arranged intermediate such cam hub and the bearing 21. Looking at the engine from the rear end, the crank shaft and the cam 63 rotate as an integral unit in a clockwise direction.

The cam 56 is driven through mechanism associated with the crank shaft. The hub of the cam 56 telescopes the hub 64 of the cam 63 and is rotatably mounted thereupon. Arranged within a bore 67 formed in the rear end of the crank shaft is a driven sleeve 68 having a helical gear 69 formed on the outer end thereof. The inner periphery of such sleeve 68 is splined to the crank shaft as indicated by the numeral 70 while the inner portion of the sleeve is formed along its entire wall with a helical spline 71. Telescoped within the driven sleeve 68 is a starter jaw 72 which is formed on its periphery with a helical spline 73 which meshes with the helical spline in the interior of the helical spline 71. Extending axially through the bore 67 and screwed into the rear crank arm is a pin 74 upon the rear end of 40 which is screwed a retainer sleeve 75 which bears against a ring 76 for retaining the starter jaw axially in a definite relation to the crank shaft, such ring 76 engaging an inwardly extending shoulder 77 extending from the starter jaw. 45 Within the bore 67 is arranged a compressed coil spring 78 which bears at one end against the crank cheek and at the other end against the driven sleeve 68, the tension of such sleeve being sufficient to normally retain the driven sleeve in 50 its rearmost position. Upon a shaft 79 carried by the rear wall of the crank case is fixed a helical gear 80 and a spur gear 81, the spur gear being arranged to mesh with an internal gear 82 formed on the cam 56. Such train of gearing is preferably arranged to drive the cam 56 from the crank shaft in an anti-clockwise direction and at one-eighth the speed thereof.

In Figs. 1 and 3 the cams 56 and 63 are shown in their desired relation when the engine is operating under its own power. In such position the lobes, for actuating the slippers of the fuel injection mechanism, are related to the crank shaft so that they are effective in a range extending between forty and twenty degrees before the pistons reach the top of their air compression strokes, the degree in the range at which the lobes cause actuation of the associated slippers is controlled by the adjustment of the ring 47. When in such relation the lobes 57, 58, 59 and 60 are 65 of such length that they raise the slippers prior to the movement of the single lobe on the cam 63 thereunder and hold the slippers in raised position so that the lobe of the faster cam will pass thereunder without effecting operation of the 70 slippers. The cam 63 is preferably fixed to the

crank shaft so that in its rotation the lobe thereon will cause actuation of the slippers of the fuel pump actuating mechanisms approximately ten degrees before the pistons reach the top of their air compression strokes. Under such conditions the spring 78 exerts sufficient force against the driven sleeve 68 to maintain it in its rear-most position and when in such position the cam 56 is effective to cause actuation of fuel injection devices.

Rotation of the crank shaft imparts rotation to the sleeve 68 through the spline connection 70 and consequently rotation of the helical gears 69 and 80 and the gears 81 and 82 cause rotation of the cam 56 from the crank shaft.

When the engine is to be started the inertia starter 34 is energized and the jaw 25 is moved axially into engagement with the starter jaw 72. The first rotation of the starter jaw 72 upon the application of the inertia starter thereto, due to the helically splined relation with the driven sleeve and its splined relation with the crank shaft, will cause a forward axial movement of the driven sleeve 68. Forward movement of the driven sleeve will cause the helical teeth of the gear 69 formed thereon, to rotate the gear 80 and through the train of gears extending therefrom to the cam 56 will impart a similar rotation thereto. This forward movement of the driven sleeve is sufficient to cause a rotation of the cam 56 in 105 an angular relation to the crank shaft such that the lobes for actuating the fuel mechanism slippers will be moved to a point where they would engage the slippers later than the time at which the slippers are engaged and actuated by the lobe 110 on the cam 63, and preferably the cam 56 is thus rotated to a position where the fuel mechanism actuating lobes thereon would engage the slippers approximately at the time the pistons reach the top of their compression strokes. When the 115 sleeve 68 has been moved to its rearmost position through the rotation of the starter jaw, continued rotation thereof by the inertia starter will cause rotation of the crank shaft and all of the driving mechanism as an integral unit, it being 120 understood that the driven sleeve 68 is moved forwardly against the tension of the spring 78 so that upon release or an over-running of the starter jaw 25 by the starter jaw 72, the spring 125 will return the gear driving mechanism to its 130 rearmost position as shown in Figs. 1 and 3. In Fig. 2 the cams 63 and 56 are illustrated in the position they assume when the starter has been applied to the starter jaw and the cam 63 in effective position. When the cam 63 is in effec- 135 tive position it will raise the slippers in advance of the lobes on the cam 56 and the single lobe thereon is of sufficient length to maintain the slippers which have been actuated to cause an injection stroke in an elevated position until such 140 time as the actuating portion of the lobes of the cam 56 have passed beneath the same. It will be seen, therefore, that when the cam 63 is effective to cause fuel injection strokes it will shield or mask the lobes on the cam 56 and vice-versa. 145 This masking relation of the cams is due to the length of the lobes and to the relation and speed of operation thereof, it being understood that upon every two revolutions of the crank shaft there will be one actuation of each of the fuel injection devices.

As the cam 63 is moving eight times as fast as the cam 56 there will be a material pressure developed behind the fuel charges being injected through the nozzle even though the cams are 150

- being rotated relatively slowly by the application of the starter. It will be seen that the cam 63 is automatically made effective through the association of the starter with the mechanism for driving the cam 56 and that the spring 68 automatically returns the cam 56 to effective position upon release of the starter, it will be understood, however, that this movement could be performed manually if desired. 80
- 10 The pressure developed behind the fuel upon the injection strokes of the pumps when the cam 63 is effective will cause a fine atomization of and pressure behind the fuel charges injected, sufficient to penetrate substantially midway of 85
- 15 the air rotating within the cylinders so that upon one revolution of compressed air in the cylinders the atomized fuel will be uniformly distributed and form a homogeneous mixture which will ignite readily under the pressure developed with 90
- 20 in the combustion chambers, and in this manner starting of a compression-ignition engine is materially assisted. Under normal temperature conditions, this form of injection requires only a few rotations of the crank shaft to cause the 95
- 25 engine to operate under its own power, and even under cold temperature conditions the addition of a glow plug or the heating of the air charges drawn into the cylinders is all that is required to result in easy starting of the engine with this 100
- 30 manner of injecting the fuel upon starting. It will also be seen that the fuel charges are delivered at substantially the highest point of compression of the air charges, when the cam 63 is in effective position, so that the greatest heat 105
- 35 developed is utilized at the proper time to cause ignition and thus assist in easy starting, and economy of operation. 110
- While there is herein described in some detail a specific embodiment of the invention, which is 40 deemed to be new and advantageous and may be specifically claimed, it is not desired to be understood that the invention is limited to the exact details of the construction, as it will be apparent that changes may be made therein without departing from the spirit or scope of the invention. 115
- What I claim is:
1. In an internal combustion engine of the compression-ignition type in which fuel and air charges are introduced separately into the combustion spaces, a device for injecting atomized liquid fuel charges under pressure into a combustion space, a crank shaft, a cam rotatably associated with the crank shaft for actuating the fuel injection device, an axially movable sleeve 120
- 55 arranged to rotate with the crank shaft, said sleeve having a gear portion formed with helical teeth, reduction gearing intermediate the sleeve and the cam including a helical gear meshing with the helical teeth of the sleeve, and a starting jaw associated with the sleeve to initially cause axial movement and then rotation of the sleeve when cranked, the axial movement of the sleeve changing the cam timing. 125
- 60 2. In an internal combustion engine of the compression-ignition type in which fuel and air charges are introduced separately into the combustion spaces, a device for injecting atomized liquid fuel charges under pressure into a combustion space, a crank shaft, a cam rotatably 130
- 65 associated with the crank shaft for actuating the fuel injection device, an axially movable sleeve arranged to rotate with the crank shaft, said sleeve having a gear portion formed with helical teeth, reduction gearing intermediate the 135
- 70 sleeve and the cam including a helical gear meshing with the helical teeth of the sleeve, a starting jaw telescoping within the sleeve and meshing helically therewith, and means associated with the 140
- 75 rod and the starting jaw for fixing the starting jaw in an axial relation with the crank shaft. 145
3. In an internal combustion engine of the compression-ignition type in which fuel and air charges are introduced separately into the combustion spaces, a device for injecting atomized liquid fuel charges under pressure into a combustion space, a crank shaft having a hollow end, a rotatable cam through which the crank shaft extends axially, said cam being arranged to ac- 150

- tuate the fuel injection device, a rod extending through the hollow end of the crank shaft and secured in fixed relation thereto, a sleeve extending into the hollow end of the crank shaft and splined to rotate with the crank shaft but in an axially adjustable relation therewith, said sleeve being formed with helical teeth, a reduction gearing including a helical gear meshing with the helical teeth of the sleeve, a starting jaw telescoping within the sleeve and meshing helically therewith, and said starting jaw having an inwardly extending flange, a retaining washer keyed to the rod and engaging the flange of the starting jaw, and a nut threaded upon the rod for securing the retainer in a definite position. 80
7. In an injection type of internal combustion engine, a crank shaft, a plunger type of fuel injection device, a pair of adjacent parallel cams, mechanism for operating the injection device in operative engagement with both of said cams, one of said cams being keyed to the crank shaft and the other cam being rotatably mounted relative thereto, said cams being normally timed so that the rotatable cam leads and shields the mechanism from actuation by the fixed cam, a sleeve fixed to the crank shaft and movable a limited extent axially thereof, said sleeve having helical teeth thereon, reduction gearing between the rotatable cam and the sleeve including a helical gear meshing with the helical sleeve teeth, a jaw helically threaded to the sleeve, a starter device adapted to engage the jaw, and means normally urging the sleeve in a direction toward the starter, rotation of the jaw by the starter initially moving the sleeve axially away from its normal position before rotating the crank shaft to rotate the reduction gearing and retard the rotatably mounted cam so that the fixed cam will lead and shield the mechanism from actuation by the rotatable cam. 100
8. In an internal combustion engine of the compression-ignition type in which fuel and air charges are introduced separately into the combustion space, a device for injecting atomized liquid fuel charges under pressure into the combustion space, a crank shaft, a cam for actuating the fuel injection device, a sleeve member arranged to rotate with the crank shaft and axially movable a limited extent relative thereto, said sleeve member having helical teeth thereon, reduction gearing in driving relation between the sleeve and the cam, said reduction gearing including a helical gear meshing with the helical teeth on the sleeve member, and means for reciprocating said sleeve axially of the crank shaft including a spring and a starting jaw, said starting jaw being rotatably mounted on the crank shaft and helically splined to the sleeve member, cranking of the jaw to start the engine moving the sleeve member axially and changing the cam position angularly, said spring being arranged to oppose axial movement of the sleeve induced by the rotation of the starting jaw. 115
9. In an internal combustion engine of the compression-ignition type in which fuel and air charges are introduced separately into a combustion space, a device for injecting atomized liquid fuel charges under pressure into the combustion space, a crank shaft, a cam rotatably associated with the crank shaft for actuating the fuel injection device, a sleeve member arranged to rotate with the crank shaft and associated therewith to be moved axially a limited extent, said sleeve member having helical teeth thereon, reduction gearing in driving relation between the sleeve and the cam, said reduction gearing including a helical gear meshing with the helical teeth on the sleeve member, rotatable means in driving relation with the sleeve member, the rotation of said means moving said sleeve axially in one direction and changing the position of the cam angularly on the crank shaft, and spring means opposing such axial movement of the sleeve member, said spring means normally maintaining said sleeve member in one extreme position of its axial movement. 120
10. In an injection type of internal combustion engine, a crank shaft, a plunger type of fuel injection device, a pair of parallel cams, mechanism for actuating the injection device arranged in operative engagement with both of said cams, one of said cams being fixed to the crank shaft and the other of said cams being rotatably mounted relative thereto, said cams being normally timed so that the rotatable cam leads and shields the mechanism from actuation by the fixed cam, a sleeve fixed to rotate with the crank shaft and movable a limited extent axially thereof, said sleeve having helical teeth thereon, reduction gearing between the rotatable cam and the sleeve including a helical gear meshing with the helical teeth of the sleeve, rotatable means having helical threads engaging with the sleeve, and a spring carried by the crank shaft and associated with the sleeve opposing axial movement thereof induced by rotation of said means, the rotation of said means moving the sleeve axially of the crank shaft and thereby rotating the reduction gearing and changing the angular position of the associated cam whereby the fixed cam will lead and shield the mechanism from actuation by the rotatably mounted cam. 125
11. In an internal combustion engine of the compression-ignition type in which fuel and air charges are introduced separately into the combustion space, a device for injecting atomized liquid fuel charges under pressure into the combustion space, a crank shaft, a cam rotatably associated with the crank shaft for actuating the fuel injection device, a sleeve arranged to rotate with the crank shaft and axially movable a limited extent relative thereto, said sleeve having a gear portion formed with helical teeth, reduction gearing intermediate the sleeve and the cam including a helical gear meshing with the helical teeth of the sleeve, resilient means urging said sleeve in one direction, and means including a starter device for moving the sleeve axially of the crank shaft, axial movement of the sleeve changing the timing of the cam. 130
